UNITED STATES PATENT OFFICE

RUPERT CASTIAUX, OF BORDEAUX, FRANCE

SHEET METAL RADIATOR

Application filed February 13, 1931, Serial No. 515,617, and in France February 17, 1930.

Such attempts as were made to build sheet metal radiators did not give satisfactory results up to the present because one contented one's self with making apparatus similar to ordinary cast iron apparatus.

This invention has for its object a rolled metal radiator in which the mechanical resistance and the conductivity of the metal are utilized to the best advantage.

10 It is composed essentially of four juxtaposed sheet metal plates; the two inner plates are thick and comprise corrugations which form vertical and horizontal passages therebetween for the circulation of the heating fluid; the outer plates are thin and comprise flutes which together with the corrugations in the thick plates form vertical passages open at the bottom and the top thereof and the walls of which are swept over by the air 20 which rises therein as a result of its increase in temperature; these various plates are welded or riveted together so as to secure the necessary stiffness and tightness.

In order to ensure a good heat conductiveness between the inner and outer plates it is preferable to galvanize or tin the structure when assembled.

An embodiment of the subject matter of the invention is shown by way of example in the drawings appended hereto.

Figure 1 is an elevational view, parts being broken away.

Figures 2 and 3 are horizontal cross sectional views taken on lines 2-2 and 3-3 of Fig. 1 respectively.

Figures 4 and 5 are vertical cross sectional views taken on lines 4-4 and 5-5 of Fig. 1 respectively.

The radiator as shown comprises two inner juxtaposed corrugated metal sheets 1 the corrugations 2 of which provide vertical tubes 3 therebetween; these corrugations end at some distance short of the upper and lower extremities of the sheets and the upper and lower edges of the said sheets are flanged inwardly so as to provide between the said flanges and the ends of the corrugations an upper supply manifold 3a and a lower discharge manifold 3b; preferably, the sectional area of these manifolds is of narrow width

while it can be as high as convenient to ensure an easy passage of the desired quantity of heating fluid; nipples 4 secured to the metal sheets 1 at the ends of manifolds 3a and 3b respectively provide for the supply 55 and discharge of the heating fluid.

In the embodiment shown the manifolds have exactly the same width as the vertical conduits 3, their lateral faces being each in one plane with the outer generatrices of the 60 corrugations providing such conduits.

Tightness between these two metal sheets is secured by a weld performed e. g. electrically.

The radiator in addition comprises two 65 outer likewise corrugated metal sheets 5 the flutes 6 of which are equal in width to the corrugations 2 of the inner metal sheets 1 and provide therewith vertical channels 7 open at the bottom and top thereof. The inner generatrices of the corrugations in the sheets 5 are laid upon the outer generatrices of the corrugations providing the conduits 3 and extend also on those lateral faces of the manifolds 3a and 3b which are located in 70 one plane with the said generatrices, so that the sheets 5 and the air channels 7 practically extend over the whole height of the radiator. The outer sheets 5 are assembled by welding or riveting with the inner metal sheets 1 so 75 as to provide a good heat conductiveness between the same along the adjacent generatrices of the corrugations and along the adjacent edges of the sheets.

The inner metal sheets 1 are thick so that 85 they can withstand the inner pressure and corrosion of the fluid; on the contrary, the outer metal sheets are of thin construction as they are not to resist any pressure and are simply swept over by the surrounding air. 90

The hot fluid comes in at the top and out at the bottom. The heat is transmitted through the inner metal sheets to the thin outer metal sheets; the latter show a considerable linear development; they are swept 95 over by the air flowing upwardly at either side thereof and thereby provide for a heat dissemination which is as efficient as possible.

Some advantages amongst those of the radiator according to the invention are its very 100

low cost, its easy manufacture along repetition work lines, its considerable lightness, its perfect stiffness, its efficiency on account of the high ascensional speed of the air with-
 5 in the conduits 7. The surface of heat transmission to the air comprises the outer surface of the sheets 1 and the inner and outer surfaces of the sheets 5; thus, it is a considerable one comparatively to the weight of the ra-
 10 diator, which itself is at least three times lighter than the lightest cast iron radiators. By the same reason, the heat output or heating power is considerable with reference to both the dimensions and the weight of the
 15 apparatus.

The metal is distributed rationally and in the manner most favourable for lightness, while affording the necessary resistance to internal pressures and external blows and
 20 guarding the apparatus against a rapid corrosion of the parts in contact with the water. Moreover, it is to be noted that sheet metal is not brittle as cast iron is, and that it can be repaired easily by welding while a burst
 25 out or broken cast iron radiator has to be scrapped.

The overall thickness e of the radiator is very small, e. g. 3", so that it can be accommodated in a shallow recess in a wall or even a
 30 partition. Securing may be obtained by means of straps with unimportant sealing work, even on a thin wall.

This radiator is also advantageous from the sanitary point of view as it has no horizontal surfaces which will retain dust, and also because the greater portion of the surface of heat-transmission to the air, particularly those of sheets 5, is at a temperature which is lower than that of the hot fluid, so that the
 40 heating is very mild and a very limited amount of heat is radiated directly.

Finally, it is to be noted that the radiator generally provides a continuous, i. e. imperforate panel, and can completely close an
 45 opening in a partition between two rooms, so as to heat both rooms at the same time without setting them into communication with each other.

It is to be understood that the embodiment as described and shown is given for indicative and by no means limitative purposes and that modifications in details can be made without thereby departing from the scope of the invention. It is understood particularly that the shape of the thick sheet corrugations as well as that of the thin sheet flutes may be varied; namely, it can be chosen so as to match with the surrounding decoration.
 55 In some cases the flutes of the thin sheets may be given a different width than that of the thick sheet corrugations.

Claims:

1. A sheet metal radiator comprising a pair of metal sheets having vertical corrugations extending over part of their height
 60

and having their upper and lower edges bent inwardly, the said sheets having their flanges and the inner generatrixes of their corrugations juxtaposed so as to provide between the said upper and lower flanges and the respective ends of the said corrugations, horizontal manifolds into which the vertical conduits formed by the said corrugations open, and a pair of metal sheets provided with vertical corrugations and applied respectively with the inner generatrixes of their corrugations against the outer generatrixes of the corrugations of the first mentioned sheets, the said sheets providing therebetween air channels open at the top and bottom thereof. 80

2. A sheet metal radiator comprising a pair of metal sheets having vertical corrugations extending over part of their height and having their upper and lower edges bent inwardly, the said sheets having their flanges and the inner generatrixes of their corrugations juxtaposed so as to provide between the said upper and lower flanges and the respective ends of the said corrugations, horizontal manifolds into which the vertical conduits formed by the said corrugations open, and a pair of metal sheets provided with vertical corrugations and applied respectively with the inner generatrixes of their corrugations against the outer generatrixes of the corrugations of the first mentioned sheets and extending also over the lateral faces of the said horizontal manifolds, the said sheets providing therebetween air conduits which extend over practically the whole height of the radiator. 90

3. In a radiator, the combination of a heating body composed of two thick welded sheet metal plates formed with vertical corrugations and having an upper and lower manifold connected together by vertical channels and presenting at the top an inlet opening for the heating fluid and at the bottom a fluid outlet, an outer casing made of thin sheet metal plates, also provided with vertical corrugations and forming with the heating body vertical channels open at their ends for the upward circulation of the air, the inner generatrixes of the corrugations of the sheet metal plates of the casing being welded to the outer generatrixes of the corrugations of the sheet metal plates of the heating body. 110

In testimony whereof I have hereunto affixed my signature.
